UNITED STATES PATENT OFFICE.

WALTER E. HUENEFIELD, OF CINCINNATI, OHIO, ASSIGNOR TO THE E. H. HUENEFIELD CO., OF CINCINNATI, OHIO.

PORTABLE KNOCKDOWN OVEN.

1,037,770.

Specification of Letters Patent. Patented Sept. 3, 1912.

Application filed February 5, 1910. Serial No. 542,355.

To all whom it may concern:

Be it known that I, WALTER E. HUENEFIELD, of Cincinnati, in the county of Hamilton and State of Ohio, have invented certain new and useful Improvements in Portable Knockdown Ovens; and I do hereby declare the following to be a full, clear, and exact description of the invention, such as will enable others skilled in the art to which 10 it appertains to make and use the same.

This invention relates to improvements in portable ovens and particularly to those of the knockdown or collapsible type,—the object of the invention being to provide an 15 oven of the character above mentioned which can be easily and quickly assembled by an inexperienced person and which, when assembled will be strong and durable.

With this object in view the invention 20 consists in certain novel features of construction and combinations of parts as hereinafter set forth and pointed out in the claim.

In the accompanying drawings, Figure 1 25 is a longitudinal sectional view of an oven embodying my improvements. Fig. 2 is a transverse vertical section. Fig. 3 is a horizontal sectional view, and Figs. 4 and 5 are detail views.

30 1 represents the top sheet of the oven provided at its ends with depending straight flanges 2 and at its front and rear edges with flanges 3, the latter having upturned flanges 3' at their free edges. The front 35 and back sheets 4 and 5 are provided at their upper edges with flanges 6 formed by bending the metal upon itself. In assembling these parts, the flanged upper edges of the front and back sheets are slid 40 into the grooves formed by the flanges 3, 3' at the front and back edges of the top sheet 1. The ends of the front and back sheets are formed with flanges 7 and the end sheets 8 of the oven are provided at 45 their vertical edges with flanges 9—10 which form grooves into which the flanges 7 on the vertical edges of the front and back sheets are received when said ends are slid to their normal positions to form the ends 50 of the oven. The upper ends of said end sheets will become disposed inside of the depending flanges 2 of the top sheet and may be bolted thereto.

The front sheet 4 is made with an opening

11, around which an inwardly projecting 55 bead 12 is formed. This opening is closed by a hinged door 14.

The front, back and end sheets of the oven are provided at their lower edges with inwardly and upwardly projecting flanges 60 13 formed by bending the metal upon itself. The bottom sheet 15 of the oven is provided along its several edges with straight depending flanges 16. This bottom sheet can be inserted through the door opening 65 in the oven front and then turned to a horizontal position and pressed downwardly, causing the straight depending flanges at its edges to enter the grooves formed by the upturned flanges 13 at the edges of the 70 front, back and end sheets of the oven. The bottom sheet is made with the usual opening 17.

A rear lining sheet 18 is disposed adjacent to the rear sheet of the oven and provided with flanges 19 to engage said rear sheet and space the lining sheet therefrom. A top lining sheet 20 is located under the top oven sheet and spaced from the latter by means of upturned flanges 21 on the lining sheet. End lining sheets 22 are disposed adjacent to the end walls of the oven and spaced from the latter by means of flanges 23. The end lining sheets 22 rest at their 75 lower ends against the bottom oven sheet 80 15 and bear at their upper ends against the top lining sheet 20,—said end lining sheets thus retaining the bottom oven sheet in place so as to effectually prevent any vertical displacement or rattling thereof. The top and 85 end lining sheets bear against the rear lining sheet and prevent displacement of the latter, while displacement of the end lining sheets is prevented by the beads 12 around the 90 door opening.

95 From the construction and arrangement of parts as above described, it will be seen that the various members composing the oven and its lining can be easily and quickly assembled to form a substantial oven structure without the necessity for the employment of bolts or rivets except possibly the bolts which secure the depending flanges at the ends of the top with the end sheets 100 of the oven.

105 The end lining sheets are provided with ribs for supporting a rack 24 and a deflector 25 over the opening in the bottom of the

oven, and said rack and deflector also assist in preventing displacement of the end lining sheets.

Having fully described my invention 5 what I claim as new and desire to secure by Letters-Patent, is,—

A portable knock down oven comprising end, front and back members, each having an inside upturned flange at its lower edge 10 forming a groove, the front and back members having detachable interlocking connection with the end members, a bottom member provided at its four edges with depending flanges resting in the grooves at the 15 lower edges of the end and front and back members, a top member having detachable interlocking connection with the front and back members, a top lining

sheet having upturned flanges, the free edges of all of which engage the under- 20 side of the top member but have no connection with the end and back members, a back lining sheet extending from the bottom member to the top member with its upper edge behind the rear edge of the top 25 lining sheet, and end lining sheets extending from the bottom member to the top lining sheet and from the back lining sheet to the front member.

In testimony whereof, I have signed this 30 specification in the presence of two subscribing witnesses.

WALTER E. HUENEFELD.
